DESIGN FOR A MINER'S TOOL

John Delmer Martin, Capels, W. Va.

Application April 22, 1938, Serial No. 76,698

Term of patent 14 years

To all whom it may concern:

Be it known that I, John Delmer Martin, a citizen of the United States, residing at Capels, in the county of McDowell and State of West Virginia, have invented a new, original, and ornamental Design for a Miner's Tool, of which the following is a specification, reference being had to the accompanying drawing, forming a part thereof, in which:

Fig. 1 is a side elevational view of a tool showing my new design;

Fig. 2 is a top plan view of the tool of Fig. 1.

I claim:

The ornamental design for a miner's tool, substantially as shown.

JOHN DELMER MARTIN.
